UNITED STATES PATENT OFFICE.

CHARLES W. GRAHAM, OF CRESTWOOD, NEW YORK, ASSIGNOR TO AMERICAN CAN COMPANY, OF NEW YORK, N. Y., A CORPORATION OF NEW JERSEY.

CAN-END-LINING MACHINE.

1,351,163.

Specification of Letters Patent. Patented Aug. 31, 1920.

Application filed March 4, 1916. Serial No. 82,056.

To all whom it may concern:

Be it known that I, CHARLES W. GRAHAM, a citizen of the United States, residing in Crestwood, in the county of Westchester and State of New York, have invented a new and useful Improvement in Can-End-Lining Machines, of which the following is a specification.

This invention relates in general to can end lining machines and has more particular reference to can end lining machines which apply a previously cut out or formed liner to the can ends. It will, however, be manifest, as the invention is better understood, that numerous features of it may have valuable application in can end lining machines wherein the liners are cut and applied in the same machines or as closely successive operations. Can end liners are frequently of fibrous material such as paper and in the form of delicate rings of large diameter which are easily distorted or torn in handling, and a mechanism to operate upon them effectively should be deliberate and certain in its action. A principal object of this invention is the provision of a can end lining machine wherein the operation of the individual parts of the machine may be relatively slow and unhurried and the machine at the same time have a relatively high capacity.

A further object of this invention is the provision of a can end lining machine which is capable of moving the liners through an opening above the liner seat in the can end which is smaller than the liner, so that the machine may be used with can ends in which the annular seaming flange extends inwardly over itself slightly as is sometimes desirable.

A further object of the invention is the provision in such a machine of means for accurately and positively taking a can end and a can end liner from separate stacks and which, after depositing them in proper relative positions, will assemble them into a unitary article.

A further object of the invention is the provision of such a machine consisting of few and simple parts and adapted to operate upon a number of can ends simultaneously.

A further object of the invention is the

provision of a mechanism which will line can ends with previously cut liners and stack them neatly so that they may be quickly and easily removed for use in other machines or for storage.

A still further object of this invention is to provide a machine of the character described having an intermittent or step by step motion and performing a complete cycle of operations at each step of its motion, the organization of the machine being such that at each step a can end is positioned, a can end liner is positioned, a ring liner is placed in a can end and a can end with its liner is discharged from the mechanism.

Other objects and advantages of the invention will be apparent as it is better understood from the following description when considered in connection with the accompanying drawings illustrating a preferred embodiment thereof.

Referring to the drawings,

Figure 1 is a side elevation of the machine;

Fig. 2 is a vertical section of the machine shown in Fig. 1 and taken on line 2—2 of Fig. 3;

Fig. 3 is a plan view of said machine;

Fig. 4 is a horizontal section on line 4—4 of Fig. 1;

Fig. 5 is a horizontal section on line 5—5 of Fig. 1;

Fig. 6 is a horizontal section showing the mechanism in the base of the machine taken on line 6—6 of Fig. 2;

Fig. 7 is a two-plane sectional view taken on line 7—7 of Fig. 4 or 5, and projected in a single plane, to show the relation of the can end feed stack, the assembling plunger and the discharge opening;

Fig. 8 is a sectional view taken along line 8—8 of Fig. 4 or 5, showing a liner feed station and an assembling station;

Fig. 9 is an enlarged detail section showing a ring liner seated in the liner slide;

Fig. 10 is a similar view showing it entering in the liner-receiving groove in the can end; and

Fig. 11 shows it in place upon the liner-receiving groove in the can end.

The mechanism shown on the drawings and used to illustrate my present invention

includes three intermittently driven turrets rotating in a fixed plane and adapted to simultaneously feed three can ends into positions to receive the can end liners. These 5 turrets are overlapped by a centrally located turret which feeds three can end liners over the three can ends positioned by the can end turrets into assembling position. The turrets when thus arranged are quiescent while 10 three plungers simultaneously move down first through the can end liner turret and into the can end turrets carrying the liners to the can ends and assembling the liners and ends into unitary articles. After return 15 movement of these plungers the turrets are moved forward again, the central turret to receive a new charge of liners and the underlying can end turrets to simultaneously eject the can ends which have been lined and receive 20 a new charge of unlined ends. The lined ends fall from the can end turrets into chutes in which they are nicely stacked, so that an attendant may remove them quickly and easily.

25 The machine shown on the drawings and embodying my present invention comprises a suitable frame A, on which are mounted three can end turrets B (Fig. 5) and a can end liner central turret C, suitable mechanism D being provided to impart desired movement to said turrets and to the other moving parts of the mechanism. Also the mechanism comprises assembling plungers E, receiving chutes F and stack supports 30 G for the unlined can ends and the liners.

The frame A consists, at the bottom, of a base a^1 in which, as will be later described, is mounted a large part of the actuating portion of the mechanism. Extending upwardly from the base a^1 , which may be a casting, are a number of posts a^2 which carry at their tops a bed-plate a^3 . It is upon this bed-plate that the turrets B and C rotate, and these turrets are partially covered by an apertured cover-plate a^4 upon which are positioned the stack supports G. This plate also carries a bearing member H for the plungers E, the drive shaft I and certain other moving elements to be later described.

50 Viewing Fig. 5 it will be noted that the turrets B, which are the can end positioning members, are each provided with three can end receiving apertures b^1 equally spaced about the center of rotation of the turrets. The can end stack supports, formed of rods g^2 , extending upwardly from the cover plate a^4 , are also three in number and are located above the path of rotative travel of the can end receiving apertures b^1 in the turrets, one above each turret. At the base of each stack support an aperture g^3 is formed through the cover-plate to permit the can end at the lower end of the stack to rest 55 upon or in the corresponding turret. These

turrets revolve in the direction of the arrows shown in Fig. 5 and are intermittently given a rotative movement in steps, each step turning it through one-third revolution. When each can end turret is idle between these steps of movement a can end is received from the stack into an aperture b^1 located therebeneath. Another of the three apertures, that located immediately in advance of the one receiving a can end, is in 70 assembling position, and while the turret is quiescent the end in it receives its can end liner. The third aperture of the three is located over a hole or aperture a^5 in the bed-plate a^3 , so that the can end carried by it, 75 which, at the preceding period of rest received a liner, may drop through the bed-plate and into an appropriately located receiving chute F. The can end liners are carried in stack supports formed of rods g^5 also extending upwardly from the cover-plate a^4 . The three of these liner stack supports and the three plungers which assemble the liners and can ends, are alternately arranged at equally spaced distances on a circumference about the center of the liner turret. Beneath each plunger an aperture e^1 and beneath each liner stack support an aperture c^1 are provided in the plate a^4 and the liner turret has six equally spaced liner-receiving apertures c^2 formed therethrough. The turrets B and the turret C move about axes which cause can ends in the turrets B to be disposed in axial alignment with can end liners in the turret C at the assembling stations which are beneath the apertures e^1 in the cover-plate. The liners are carried in their apertures upon small inwardly extending ribs or flanges c^3 , one of which is located beneath the top of each aperture c^2 a distance equal substantially to the thickness of a liner, so that when the turret comes to rest the stacks of liners resting at their bottoms in the aperture c^1 of the cover-plate 90 will move down to permit a single liner to be positioned in each of the three liner receiving apertures of the turret C which are in proper registration with the stack supports. This turret has step by step movement equal to one-sixth of a revolution and 95 after the liners are simultaneously acquired by the three registering apertures in the turret the next advance or step carries them to the assembling stations which, as has been already said, alternate circumferentially with the stack supports for the can end liners. When in this position the three plungers move 100 downwardly to place the liners in the can ends. Each of these plungers comprises a head e^2 moving in and guided by an appropriate aperture e^1 in the cover-plate. Extending upwardly from this head is a stem e^3 having a bearing in an arm e^4 of the bearing member or housing H. The stem 105 extends on upwardly above the arm e^4

110

115

120

125

130

through a second bearing e^5 and is pressed downwardly by a spring e^6 engaging at the upper end the lower end of the bearing e^5 and at the lower end a stop e^7 threaded on the stem e^8 . At appropriate intervals the plungers are lifted by a cam e^8 on the upper and active face e^9 of which rides a roller e^{10} upon a stud e^{11} secured to the upper end of each plunger stem. The plungers are normally held up by the cam and are released when a set of liners and can ends are at the assembling stations. When released they move downwardly through the apertures e^1 and into engagement with the liners carried on the ledges or flanges e^3 . The outside diameters of these plungers are sufficiently less than the inside diameters of the flanges, so that the edges of the liners which rest on the flanges may be bent back and the liners forced past them (Fig. 9). The liners are carried on down to the can ends which are positioned just beneath them, these can ends being indicated on the drawings at M and the liners indicated on the drawings at N. Each can end is provided with a shoulder m^1 flaring slightly from the central part m^2 of the can end to the liner seat m^3 of the can end flange. The outer edge of the flange is bent up, and slightly inwardly if desired, at m^4 and the edge n^1 of the liner may be forced by it (Fig. 10) in the manner in which it was forced by the flange e^3 of the liner turret. These liners may therefore, if desired, be constructed of diameter greater than the internal diameter of the edge of the can end, the plungers being capable of pushing them past the restricted opening in the flange, and being capable also of seating them tightly about the shoulders m^1 (Fig. 11) if the can end liners be given an internal diameter less slightly than the largest external diameter of the shoulder m^1 .

The lined can ends are carried from the assembling stations to above the apertures a^5 in the bed-plate a^3 , and when positioned centrally thereof the next period of rest of the turrets B occurs. The lined can ends fall through the apertures a^5 into three chutes F, each consisting in the present instance of a sheet of suitable material bent to channel shape form and partially closed at its bottom f^1 . These sheets are held beneath the apertures a^5 in inclined position by brackets f^2 secured to the sheets and to the under side of the bed-plate. The outer face of each sheet is opened and the bottom is cut away at f^3 to permit the operator to lift out the stack of lined can ends received by the chute as occasion may render desirable.

The turrets and the plungers are caused to operate in synchronism through power transmitting mechanism, as will now be described. The main power shaft I has bear-

ings i^1 in the bearing member H and carries at one end a pulley i^2 . Mounted upon it is a bevel pinion i^3 which, through the pulley and shaft, receives continued rotation during the operation of the machine. The bevel pinion i^3 meshes with a bevel gear i^4 secured by a pin i^5 upon the end of a vertically and centrally disposed shaft i^6 . Mounted also upon this shaft and in the present instance shown as being constructed integral with the bevel gear i^4 is the cam e^9 , this cam having a succession of raised parts alternating with depressions which, in the movement of the cam, cause the plungers to rise and fall in their operative and return strokes.

Upon the lower end of the shaft i^6 , which has a lower bearing d^1 in the bottom plate of the base a^1 , is fixed a spur gear d^2 . This spur gear meshes with a pinion d^3 upon a vertically disposed stub shaft d^4 , journaled at its ends at d^5 in the housing formed by the base a^1 and a bottom-plate d^6 . From the pinion d^3 an intermittent motion is imparted to a quill or sleeve d^7 disposed about the shaft i^6 through a Geneva movement D. This movement, in the present instance, consists of a driving member d^8 fixed by a pin d^9 upon the shaft d^4 and having extending downwardly from its under face three equally spaced roller teeth d^{10} which mesh with a 6-point Geneva gear d^{11} fastened upon the quill or sleeve d^7 . The liner turret has a six step per revolution movement and turns with the Geneva gear d^{11} , the engagement of each tooth d^{10} causing the liner turret C to advance one step.

A spur gear d^{12} is also fixed upon the quill or sleeve d^7 and this meshes with three pinions d^{13} each secured at d^{14} upon the lower end of a driving rod d^{15} of a can end turret. These rods are journaled at one end at d^{16} in the base a^1 and at the other (upper) at d^{17} in the bed-plate a^3 . Each shaft d^{15} is secured at its upper end to a corresponding can end turret B. The teeth upon the spur gear d^{12} and on the pinions d^{13} are in the ratio of two to one, so that for each rotation of the sleeve or quill two rotations will be given the can end turrets. This causes the can end and liner turrets to operate in synchronism as the liner turret has six stations and each can end turret three. The parts are adjusted so that a can end aperture of each can end turret is in alinement with a liner-carrying aperture in the liner turret. Thus three or one-half of the apertures in the liner-carrying turret are located at assembling stations and one-third of the apertures in the can end carrying turrets are in assembling relation thereto. The other liner apertures in the liner turret are in position beneath the stack supports, one of which is located midway circumferentially between each succeeding pair of assembling stations.

Of the other apertures in the can end turrets, one of each is located over a discharge chute or aperture and the other under the can end stack supports so that each advance 5 of the machine brings three liners and three can ends into proper relation and also causes the ejection of three finished ends into the several chutes. The liner turret and the can end turrets rotate in horizontal planes 10 and the assembling plungers at appropriate intervals move down at right angles thereto to assemble the liners and can ends. The liner turret overlaps the can end turrets a sufficient distance to permit them in their 15 movement to bring the liners over the can ends.

It will be manifest from the foregoing that the organization of the machine embodying my present invention is such that 20 for each step of its movement three can ends and three can end liners are separately selected from their stacks; that also at each such step three ring or can end liners are assembled with the can ends; and that also 25 at each such step three lined can ends are ejected into the receiving chute.

It is thought that the invention and many 30 of its attendant advantages will be understood from the foregoing description, and it will be apparent that various changes may 35 be made in the form, construction and arrangement of the parts without departing from the spirit and scope of the invention or sacrificing any of its material advantages, the form hereinbefore described being merely a preferred embodiment thereof.

I claim:—

1. In a machine for assembling liners and can ends, the combination of a central 40 intermittently rotatable carrier, means adapted to deliver thereto elements to be assembled, carriers which are intermittently rotatable and which are arranged and spaced around said central carrier and intersect therewith for the alinement of said elements with other elements, means for delivering said other elements to each of said spaced carriers, and sets of assembling devices arranged around the center of the 45 central carrier and alternating with the element-delivering means thereof, whereby a plurality of elements are received by the central carrier at the same intermission during which a plurality of other elements are 50 assembled with can ends, the central carrier and the other carriers having simultaneous receiving and assembling intermissions of movement.

2. In a machine for assembling liners and 60 can ends, the combination of a central intermittently rotatable carrier, stack holders adapted to deliver thereto elements to be assembled, carriers which are intermittently rotatable and which are arranged and 65 spaced around said central carrier and in-

tersect therewith for the alinement of said elements with other elements, a stack holder for each of said spaced carriers, and sets of assembling devices arranged around the center of the central carrier and alternating with the stack holders thereof, whereby a plurality of elements are received by the central carrier at the same intermission during which a plurality of other elements are assembled with can ends, the central carrier and the other carriers having simultaneous receiving and assembling intermissions of movement. 70

3. The combination of a central rotatable ring liner carrier, means adapted to deliver ring liners thereto, can end carriers which are rotatable and which are arranged and spaced around said ring liner carrier and intersect therewith for the alinement of the can ends with the ring liners, means for delivering can ends to each of said can end carriers, and sets of assembling devices arranged around the center of the central carrier and alternating with the ring liner delivering means, whereby a plurality of ring liners are received by the central carrier while a plurality of other ring liners are assembled with can ends. 80

4. In a machine for assembling liners and can ends, the combination of a central intermittently rotatable carrier having apertures, stack holders adapted to deliver thereto elements to be assembled, carriers which have apertures and are intermittently rotatable and which are arranged and 95 spaced around said central carrier and intersect therewith for the alinement of said elements with other elements, the liner-receiving apertures having shoulders, a stack holder for each of said spaced carriers, and sets of assembling devices arranged around the center of the central carrier and alternating with the stack holders thereof, whereby a plurality of elements are received by the central carrier at the same intermission during which a plurality of other elements are assembled with can ends, said carriers having simultaneous receiving and assembling intermissions of movement. 100

5. In a machine for assembling liners and can ends, the combination of a central intermittently rotatable carrier, stack holders adapted to deliver thereto elements to be assembled, carriers which are intermittently rotatable and which are arranged and spaced around said central carrier and intersect therewith for the alinement of said elements with other elements, a stack holder for each of said spaced carriers, and sets of assembling devices arranged around the 115 center of the central carrier and alternating with the stack holders thereof, whereby a plurality of elements are received by the central carrier at the same intermission during which a plurality of other elements are 120 assembled with can ends.

assembled with can ends, the central carrier having receiving and assembling intermissions of movement and the other carriers having receiving, assembling and discharging intermissions.

6. The combination of a central intermittently rotatable ring liner carrier, stack holders adapted to deliver ring liners thereto, can end carriers which are intermittently rotatable and which are arranged and spaced around said ring liner carrier and intersect therewith for the alinement of the can ends with the ring liners, a stack holder for each of said can end carriers, and sets of assembling devices arranged around the center of the central carrier and alternating with the ring liner stack holders, whereby a plurality of ring liners are received by the central carrier at the same intermission during which a plurality of other ring liners are assembled with can ends, the central carrier having receiving and assembling intermissions of movement and the other carriers having receiving, assembling and discharging intermissions.

7. The combination of a central intermittently rotatable ring liner carrier having shouldered apertures, stack holders adapted to deliver ring liners thereto, can end carriers having apertures and which are intermittently rotatable and which are arranged and spaced around said ring liner carrier and intersect therewith for the alinement of the can ends with the ring liners, a stack holder for each of said can end carriers, and sets of assembling devices arranged around the center of the central carrier and alternating with the ring liner stack holders, whereby a plurality of ring liners are received by the central carrier at the same intermission during which a plurality of other ring liners are assembled with can ends, the central carrier having receiving and assembling intermissions of movement and the other carriers having receiving and assembling intermissions.

8. The combination of a central rotary turret and a plurality of outer rotary turrets lapping said inner turret and co-operating therewith for the simultaneous assembly and discharge of a plurality of can-closing devices, each of said devices comprising two elements, namely, a flanged can end and a ring liner seated on the flange of said can end; means for feeding one kind of said elements to said central turret; means for feeding the other kind of said elements to the outer turrets; mechanism connected with all of said turrets for giving them intermittent rotation, the ring liners and the can ends being thereby alined one with the other at several assembling stations at periods of rest of said turrets; assembling plungers arranged at said assembling stations and adapted to first engage the ring liners and

to pass thence to the several can ends alined therewith; and means for operating the plungers at said periods of rest.

9. The combination of a central rotary turret and a plurality of outer rotary turrets lapping said inner turret and co-operating therewith for the simultaneous assembly and discharge of a plurality of can-closing devices, each of said devices comprising two elements, namely, a flanged can end and a ring liner seated on the flange of said can end; means for feeding one kind of said elements to said central turret; means for feeding the other kind of said elements to the outer turrets; mechanism connected with all of said turrets for giving them intermittent rotation, the ring liners and the can ends being thereby alined one with the other at several assembling stations at periods of rest of said turrets; assembling plungers arranged at said assembling stations and adapted to first engage the ring liners and to pass thence to the several can ends alined therewith; said turrets being provided with apertures for holding and carrying said elements to be assembled, and the apertures for holding the ring liners having supporting shoulders; and means for operating the plungers at said periods of rest.

10. The combination of a central intermittently rotatable turret having ring liner receiving and carrying apertures, said turret being rotatable to move the apertures to receiving and assembling stations respectively; a feeding device for feeding ring liners to said apertures, there being such a feeding device for each pair of apertures; assembling devices at said assembling stations, each located to be in line with an aperture containing a ring liner at an interval of rest of said central turret; can end carrying turrets equal in number to said assembling devices and provided with can end holding means and intermittently rotatable to carry the holding means to receiving, assembling and can end discharging stations respectively, the assembling stations of the apertures of the central turret coinciding respectively with the several said assembling stations of the second named turrets; can end feeding devices at the receiving stations of the can end carrying turrets; and actuating means for giving to all of said turrets the said intermittent movements.

11. The combination of a central intermittently rotatable turret having ring liner receiving and carrying shouldered apertures, said turret being rotatable to move the apertures to receiving and assembling stations respectively; a feeding device for feeding ring liners to said apertures, there being such a feeding device for each pair of apertures; annular assembling plungers at said assembling stations, each located to be in line with an aperture containing a ring

liner at an interval of rest of said central 5
turret; can end carrying turrets equal in
number to said assembling devices and pro-
vided with can end holding apertures and
intermittently rotatable to carry their hold-
ing apertures to receiving, assembling and
can end discharging stations respectively,
their assembling stations coinciding respec-
tively with the several said assembling sta-
tions of the central turret; can end feeding
devices at the receiving stations of the can
end carrying turrets; actuating means for
giving to all of said turrets the said inter-
mittent movements; and a bottom plate under
10 the can end carrying turrets and having
discharge apertures at the said discharging
stations.

12. In a can end lining machine, in combi-
nation: a central rotatable liner feeder hav-
ing a plurality of liner receiving apertures,
said feeder being rotatable to move the aper-
tures to receiving and assembling stations
respectively; stack holders at said receiving
stations from which holders liners are indi-
vidually taken by said feeder and trans-
ported to said assembling stations, movable
can end feeders provided with can end hold-
ing means and arranged and spaced around
said central feeder and each having a can
end receiving station to which respectively
their said holding means are moved, an as-
sembling station and a can end delivery station,
said assembling stations of the can end feeders
coinciding respectively with the
30 assembling stations of said central liner
feeder, stack holders for can ends arranged
respectively at the can end receiving stations
of the said can end feeders, means for ro-
tating said central feeder intermittently each
35 step being from a receiving station to an as-
sembling station, and for moving the can
end feeders intermittently and correspond-
ingly each step being from one of their sta-
tions to the next of their stations, assem-
bling devices arranged at said assembling
40 stations for removing the liners from the
central feeder and depositing them respec-
tively in the can ends carried by the can
end feeders, and means for operating said
assembling devices during the intervals be-
50 tween the said steps of movement of the
said liner and can end feeders.

13. In a can end lining machine, in combi-
nation: a central rotatable liner feeding
55 turret having liner holding means which are
rotatable to a plurality of liner receiving
stations and assembling stations respec-
tively; stack holders at said receiving stations
from which holders liners are indi-
vidually taken by said turret and trans-
ported to said assembling stations, rotatable
60 can end feeders arranged and spaced around
said central turret and each having can end
holding means which are rotatable to a can
end receiving station, an assembling station
65 and a can end delivery station respectively,

said assembling stations of the can end
feeders coinciding respectively with the as-
sembling stations of said central turret,
stack holders for can ends arranged respec-
tively at the can end receiving stations of
70 the can end feeders, means for rotating said
central turret intermittently each step being
from a receiving station to an assembling
station, and for rotating the can end receiv-
ing feeders intermittently and correspond-
ingly, each step being from one of their sta-
tions to the next of their stations, an assem-
bling device arranged at each of said assem-
bling stations for removing the liners from
80 the central turret and depositing them re-
spectively in the can ends carried by the can
end feeders, and means for operating said
assembling devices during the intervals be-
tween the said steps of movement of the said
85 turret and can end feeders.

14. In a can end lining machine, in combi-
nation: a central rotatable liner feeding
turret having liner holding apertures which
are rotatable to three liner receiving stations
and three assembling stations respectively;
stack holders at said receiving stations from
90 which holders liners are individually taken
by said turret and transported to said assem-
bling stations, three can end feeding
turrets arranged and spaced around said
central turret and each having can end hold-
ing means rotatable to a can end receiving
95 station, an assembling station and a can end
delivery station respectively, said assem-
bling stations of the can end feeding turrets
coinciding respectively with the assembling
stations of said central turret, stack holders
100 for can ends arranged respectively at the
can end receiving stations of the can end
feeding turrets, means for rotating said cen-
tral turret intermittently each step being
from a receiving station to an assembling
105 station, and for rotating the can end receiv-
ing turrets intermittently and correspond-
ingly each step being from one of their sta-
tions to the next of their stations, three
assembling devices arranged at said assem-
110 bling stations for removing the liners from
the central turret and depositing them re-
spectively in the can ends carried by the can
end feeding turrets, and means for operat-
ing said assembling devices during the inter-
vals between the said steps of movement of
115 the turrets.

15. In a can end lining machine, in combi-
nation: a central rotatable liner feeding
turret having shouldered perforations
which are rotatable to a plurality of liner
receiving stations and a corresponding
120 number of assembling stations respectively;
stack holders at said receiving stations from
which holders liners are individually taken
by said turret and transported to said assem-
bling station, a plurality of can end
125

- feeding turrets arranged and spaced around said central turret and each having can end holding means rotatable to a can end receiving station, an assembling station and 5 a can end delivery station respectively, the perforations in the liner feeding turret being a multiple of the number of said can end feeding turrets, and said assembling stations of the can end feeding turrets coinciding respectively with the assembling stations of said central turret, stack holders for can ends arranged respectively at the can end receiving stations of the can end feeding turrets, means for rotating said central turret intermittently each step being from a receiving station to an assembling station, and for rotating the can end receiving turrets intermittently and correspondingly each step being from one of 10 their stations to the next of their stations, a plurality of assembling devices arranged at said assembling stations for removing the liners from the central turret and depositing them respectively in the can ends 15 carried by the can end feeding turrets, and means for operating said assembling devices during the intervals between the said steps of movement of the turrets.
16. The combination of a central rotary 20 turret having spaced carrying means rotatable to receiving and assembling stations respectively, and a plurality of outer rotary turrets having holding means which are rotatable to receiving and assembling and delivering stations respectively, and lapsing said inner turret and coöperating therewith for the simultaneous assembly and discharge of a plurality of can closing devices, each of said devices comprising two 25 elements, namely, a flanged can end and a ring liner seated on the flange of said can end, the number of carrying means on the central turret being a multiple of the number of said outer turrets; means for feeding 30 one kind of said elements to said central turret; means for feeding the other kind of said elements to the outer turrets; mechanism connected with all of said turrets for giving them intermittent rotation, the ring 35 liners and the can ends being thereby alined 40 one with the other at several assembling stations at periods of rest of said turrets; assembling plungers arranged at said assembling stations and adapted to first engage the ring liners and to pass thence to the 45 several can ends alined therewith; and means for operating the plungers at said 50 periods of rest.
17. In a machine for assembling two sets 55 of articles in pairs, the combination of a carrier for one set of articles having a series of receptacles therefor, means for delivering said articles simultaneously to alternate of 60 said receptacles, assembling devices arranged to operate simultaneously at the
- other alternate receptacles on articles of the two sets which have been alined with each other, means for delivering the other set of said articles simultaneously in line with the second mentioned alternate charged 70 receptacles and in line with said assembling devices, means whereby the assembled articles are discharged, and means for actuating the carrier to move its charged receptacles progressively from said article-delivering means to said assembling devices and its discharged receptacles from said assembling devices to said delivering devices.
18. In a machine for assembling ring 80 liners and can ends, the combination of a carrier for one kind of said articles having a series of receptacles therefor, means for delivering said kind of articles simultaneously to alternate of said receptacles, assembling devices arranged to operate simultaneously at the other alternate receptacles on ring liners and can ends which have been alined, means for delivering the other kind of said articles simultaneously in line 85 with the second mentioned alternate receptacles and in line with said assembling devices, the said receptacles and delivering means forming, when alined, a series of apertures in which the assembling devices 90 operate, and means for actuating the carrier to move its article holding receptacles progressively from said article-delivering means to said assembling devices.
19. In a machine for assembling ring 100 liners and can ends, the combination of a carrier for ring liners having a series of shouldered receptacles therefor, means for delivering said liners simultaneously to alternate of said receptacles, assembling devices arranged to operate simultaneously at the other alternate receptacles on ring liners and can ends which have been alined, means for delivering the can ends simultaneously in line with the second mentioned alternate receptacles and in line with said assembling devices, and means for actuating the carrier to move its article-holding receptacles progressively from said delivering means to 105 said assembling devices.
20. In a machine for assembling ring 110 liners and can ends, the combination of a carrier for ring liners having a series of receptacles therefor, means for delivering said liners simultaneously to alternate of 120 said receptacles, assembling devices arranged to operate simultaneously at the other alternate receptacles on ring liners and can ends which have been alined, means for delivering the can ends simultaneously in line with the second mentioned alternate receptacles and in line with said assembling devices, the said receptacles and delivering means forming, when alined, a series of apertures in which the assem- 125
- 130

bling devices operate, and means for actuating the carrier to move its article-holding receptacles progressively from said delivering means to said assembling devices.

5 21. In a machine for assembling ring liners and can ends, the combination of an endless carrier for one kind of said articles having a series of receptacles therefor, means for delivering said kind of articles simultaneously to alternate of said receptacles, assembling devices arranged to operate simultaneously at the other alternate receptacles on ring liners and can ends which have been alined, means for delivering 10 the other kind of said articles simultaneously in line with the second mentioned alternate receptacles and in line with said assembling devices, and means for actuating the carrier to move its article-delivering 15 receptacles progressively from said assembling devices.

20 22. In a machine for assembling ring liners and can ends, the combination of a continuous and intermittently moving car-

rier for one kind of said articles having 25 a series of receptacles therefor, means for delivering said kind of articles simultaneously to alternate of said receptacles, assembling devices arranged to operate simultaneously at the other alternate receptacles on ring liners and can ends which have been alined, means for delivering 30 the other kind of said articles simultaneously in line with the second mentioned alternate receptacles and in line with 35 said assembling devices, and means for actuating the carrier to move its article-delivering receptacles progressively from said article-delivering means to said assembling devices.

40 In testimony whereof I have hereunto set my hand in the presence of two subscribing witnesses.

CHARLES W. GRAHAM.
